(57) **CLAIM**

The ornamental design for a portable article carrier, as shown and described.

DESCRIPTION

FIG. 1 is a front perspective view of a portable article carrier showing a first embodiment of my new design;

FIG. 2 is a front elevational view of the portable article carrier of FIG. 1;

FIG. 3 is a rear elevational view of the portable article carrier of FIG. 1;

FIG. 4 is a left side elevational view of the portable article carrier of FIG. 1;

FIG. 5 is a right side elevational view of the portable article carrier of FIG. 1;

FIG. 6 is a top plan view of the portable article carrier of FIG. 1;

FIG. 7 is a bottom plan view of the portable article carrier of FIG. 1;

FIG. 8 is a front, right-side perspective view of the portable article carrier of FIG. 1, showing the carrier in an open position;

FIG. 9 is a front, left-side perspective view of the portable article carrier of FIG. 1, showing the carrier in an open position;

FIG. 10 is a rear, left-side perspective view of the portable article carrier of FIG. 1, showing the carrier in an open position; and,

FIG. 11 is a rear, right-side perspective view of the portable article carrier of FIG. 1, showing the carrier in an open position.

The dashed lines (dash-dash-dash) show portions of the portable article carrier that form no part of the claimed design. The dashed lines (dash-short dash-long dash) immediately adjacent to the shaded areas in the figures represent the boundaries of the claimed design. None of the broken lines form any part of the claimed design.
